(57) CLAIM

The ornamental design for a vehicle center control panel, as shown and described.

DESCRIPTION

FIG. 1 is a perspective view of a vehicle center control panel showing our new design; and,

FIG. 2 is an front elevational view thereof.

The broken line showings of the vent louvers, the audio system controls, the indicia on the knobs, and the gear shift area are for illustrative purposes only and form no part of the claimed design.

1 Claim, 2 Drawing Sheets

FIG. 2

UNITED STATES PATENT AND TRADEMARK OFFICE
CERTIFICATE OF CORRECTION

PATENT NO. : Des. 528,485 S
